ABSTRACT: A vibration-resistant contact structure including a movable contact for interconnecting two fixed contacts. The movable contact includes a rigid blade and a flexible blade. The flexible blade engages the fixed contacts when the movable contact is urged into partially closed connection. When fully closed, the flexible blade is deflected substantially flush up against the rigid blade. During vibration, the movable contact need not remain absolutely motionless but can move within the range established between the partially closed and fully closed positions and continuity is retained. In one embodiment, the flexible blade is secured to the rigid blade at a point between its ends. In another, the flexible blade is attached to one of the fixed contacts, and in still another the flexible blade is slidably mounted on the contact actuator. Use of contact structures of this type is illustrated in a coaxial switch including provision for make-before-break operation.

VIBRATION-RESISTANT CONTACT STRUCTURE FOR COAXIAL SWITCH

BACKGROUND OF THE INVENTION

The present invention relates to electrical contact structure. More specifically, the invention relates to an improved contact structure which maintains circuit continuity when subjected to violent forces due to acceleration and vibration.

One of the major problems with electrical contacts is their sensitivity to vibration. A result of this sensitivity is that electrical connections will be interrupted if the contacts are subjected to external shock. Vibration and shock sensitivity are particularly troublesome in certain applications. Spacecraft, for example, require a variety of electrical switches which must be capable of withstanding high levels of shock and vibration without interruption of circuit continuity.

Previous attempts to avoid vibration problems have concentrated primarily on increasing the amount of pressure applied to the contacts of the switch to hold them in engagement. While this approach has been nominally successful, the use of increased force requires larger armatures, biasing springs, etc. which increase the size and weight of the switch. Even the use of such increased force has not been totally successful since it has usually been applied in combination with ordinary contact configurations which must be held absolutely secure. With such contact configurations, even the slightest movement results in interrupting electrical connections.

Another approach to the problem of vibration sensitivity uses contact structures which include a movable contact having two or more elements. These elements are generally separated by some type of springlike material such as coiled springs, foam rubber, etc. The presence of the springlike material acts to make the contact structure less sensitive to vibration since the individual elements of the movable contact are allowed to move a certain amount without interrupting circuit continuity. Such structures, however, are difficult to assemble and adjust, particularly in small switches.

It has also been suggested that circuit interruption due to vibration can be avoided by providing two or more movable contacts bridging a single pair of fixed contacts. The movable contacts are connected to a common actuator but are of different construction so that their resonant frequencies are different. In such a configuration, one of the movable contacts can be allowed to vibrate out of connection without interrupting circuit continuity since the other movable contact, having different resonant characteristics, will remain firmly engaged.

Finally, the problem of vibration sensitivity is further aggravated in a coaxial switch which has several inputs and outputs and requires make-before-break operation. The additional mechanical elements necessary to provide this type of operation increase the size and weight of the switch and also increase its sensitivity to shock and vibration.

It is an object of the present invention to provide a novel contact structure which maintains electrical connection during severe conditions of shock or vibration.

It is a further object of the present invention to provide a vibration-resistant contact structure without an increase in size and/or weight.

It is still further object of the present invention to provide a novel contact structure which allows a predetermined amount of contact movement without interruption of circuit continuity.

It is an additional object of the present invention to provide a novel coaxial switch of the make-before-break type, employing vibration-resistant contact structures.

Briefly, the present invention accomplishes these and other objects by providing a movable contact for engaging fixed contacts. The movable contact includes a relatively rigid member and a relatively flexible member whereby electrical contact is maintained by the flexible member during movement of the contact structure.

BRIEF DESCRIPTION OF THE DRAWINGS

FIG. 1 is a perspective view of a coaxial switch utilizing a preferred embodiment of the contact structure comprising the present invention.

FIG. 2 is a longitudinal sectional view along section line 2-2 of a portion of the coaxial switch of FIG. 1.

FIGS. 3a, 3b and 3c are diagrammatic views showing a preferred embodiment of the contact structure comprising the present invention in the open, partially closed and closed positions.

FIGS. 4a, 4b and 4c are similar views showing a pair of the contact structures in the open, partially closed, and closed positions, respectively, forming a make-before-break coaxial switch.

FIG. 5 is a diagrammatic view of an alternative embodiment of the contact structure comprising the present invention.

FIG. 6 is a diagrammatic view of an additional alternative embodiment of the contact structure comprising the present invention.

FIG. 7 is a diagrammatic view illustrating the construction of the contact blades in the embodiment of FIG. 6.

DESCRIPTION OF THE PREFERRED EMBODIMENTS

Turning to FIG. 1, there is shown a perspective view of a coaxial switch which includes a preferred embodiment of the contact structure comprising the present invention. The coaxial switch of FIG. 1 includes two main portions, the contact structure indicated generally at 11 and the energizing mechanism shown generally at 31. The energizing portion 31 forms no part of the present invention, and may comprise, for example, an electromagnet which has appropriate external connections (not shown) for connection to a source of electrical power for energizing and deenergizing the switch.

The contact structure 11 includes sidewalls 10 and 12 and a bottom plate 13.

With reference to FIG. 2, there is shown a longitudinal view along section line 2-2 of a coaxial switch of FIG. 1. Coaxial connectors 14, 15 and 16 may be located in bottom plate 13 which is constructed of a suitable electrically conductive material so as to constitute means for electrically interconnecting the outer conductors of coaxial connectors 14, 15 and 16.

Coaxial connector 14 may, for example, consist of an outer shell 17 which is constructed of an electrically conductive material and acts as the outer conductor. An inner conductor 18 is also provided, the two conductors 17 and 18 being separated by suitable insulation material indicated generally at 19. The outer shell 17 is threaded so as to allow for connection to a coaxial cable (not shown). Connectors 15 and 16 are similarly constructed.

Coaxial connector 15 may serve as the input connector whereas the coaxial conductors 14 and 16 constitute first and second output connectors in applications where a signal is inserted by way of input connector 15 and may be selectively switched to either output connector 14 or output connector 16. It is also possible to apply such a coaxial switch by feeding input signals to connectors 14 and 16 and selectively applying one of these input signals to connector 15.

To connect input connector 15 to output connector 14, there is provided a movable contact indicated generally at 20. The movable contact 20 is arranged so as to interconnect first and second fixed contacts such as the inner conductors 18 and 18' of connectors 14 and 15. Similarly, there is provided a second movable contact indicated generally at 21 which is used to connect input connector 15 to output connector 16 by way of a mechanical connection from inner conductor 18' to inner conductor 18''.

While the present invention is illustrated by way of a coaxial switch which selectively interconnects three connectors, it will be evident that the contact structure disclosed could be used equally well in a coaxial switch having any number of connectors for selective engagement.

Movable contact 21 consists of two elongated blades 22 and 23 constructed of an electrically conductive material. In this embodiment, blades 22 and 23 are substantially the same in length and width. Blade 22, however, is relatively thick and constructed of an electrically conductive material which is relatively rigid. For example, blade 22 may be about 0.025 inch thick, constructed of gold-plated beryllium copper. Blade 23, on the other hand, is relatively thin and flexible and formed in a substantially arcuate shape. The material used for blade 23 is an electrically conductive spring material such as beryllium copper or phosphor bronze, gold plated. In one particular application blade 23 was 0.004 inch thick.

Movable contact 20 is similarly constructed.

To form the movable contacts 20 and 21, the two blades 22 and 23 are joined at some point between the ends thereof such as, for example, at approximately the center, by spot welding.

Movable contacts 20 and 21 are secured to movable actuators 24 and 25, respectively. These actuators may comprise cylindrical rods of low-loss plastic material rigidly secured to the movable contacts in any convenient manner. As illustrated in FIG. 2, the actuators 24 and 25 extend through a plate 26. The actuators 24 and 25 are joined at their upper ends to opposite ends of a rocker arm 27 which is mounted for pivotal movement about axis 28. Rocker arm 27 may be biased in one position as by a compression spring 29.

To operate the switch, a force (indicated by the arrow 30) is exerted on one end of the rocker arm. Application of such an operating force will cause rocker arm 27 to pivot, thereby forcing actuator 25 and its associated movable contact 21 to move downwardly and engage inner conductors 18' and 18''. At the same time, actuator 24 will move upwardly and lift movable contact 20 so as to disengage the connection between inner conductors 18 and 18'.

The switch of FIG. 1 has an inherent ability to withstand shock and vibration resulting from the structure of rocker arm 27. Since the distance from the pivot point 28 to the actuator 24 will generally be substantially the same as the distance from the pivot point 28 to the actuator 25, any accelerating forces will be balanced by these substantially identical moment arms. That is, accelerating forces which tend to lift actuator 24 will have a similar effect on actuator 25. However, since actuator 25 is connected to the opposite end of the rocker arm 27, these forces will balance each other so that the movable contacts 20 and 21 will maintain their positions during severe shock or vibration conditions.

The operation of the movable contact 21 can be seen in detail by referring to FIGS. 3a, 3b and 3c. In FIG. 3a, movable contact 21 is shown in the open position. Thus, rigid blade 22 is held by actuator 25 up against plate 26. Flexible blade 23 is in its natural, undeflected position so that the ends of the blades 22 and 23 are spaced apart. In this position the flexible blade 23 is held above the inner conductors 18' and 18'' and no electrical contact is established. In FIG. 3b actuator 15 is shown in a first position of its downward motion. At this first position, the flexible blade 23 comes into contact with the inner conductors 18' and 18''. At this point, electrical contact is established, but the flexible blade 23 has not yet begun to deflect toward the rigid blade 22. This is the partially closed position.

In FIG. 3c, actuator 25 is shown in the completely closed position where it has forced movable contact 21 downwardly to the point where flexible blade 23 has deflected upwardly against rigid blade 22 and the two blades are substantially flush with one another. At this point, the actuator 25 has traveled its full distance.

In the partially closed position of FIG. 3b, the connection between the movable contact 21 and the inner conductors 18' and 18'' is firmly established. It will be noted, however, that the rigid blade 22 still has a distance t to travel before the contact 21 is in the fully closed position of FIG. 3c. It is clear from these figures that electrical connection will be maintained as long as contact 21 is in, or somewhere between, the positions shown in FIGS. 3b and 3c. Therefore, if the switch is subjected to vibration, contact 21 need not maintain the fully closed

position of FIG. 3c, but rather may be allowed to move any amount less than t without interrupting circuit continuity. In addition, the low inertia of the flexible blade 23 makes it inherently less susceptible to such movement during vibration.

5 The distance t which the contact 21 can move during vibration is, of course, directly related to the separation between the ends of the blades 22 and 23. Thus, the contact structure can be made more or less sensitive to vibration by varying the material and/or curvature of the flexible blade 23. In one application, flexible blade 23 was approximately 0.800 inch long constructed of beryllium copper, 0.004 inch thick. Its radius of curvature was such that, when attached to rigid blade 22, the separation between the ends of the two blades was 0.012 inch to 0.016 inch. Thus, in this application, contact 21 could move 0.012 inch to 0.016 inch when subjected to vibration without interrupting circuit continuity. This structure successfully passed a vibration requirement of 10—55 c.p.s. at 0.100 D.A. and 55—500 c.p.s. at 10G acceleration for 3 hours in each of three mutually perpendicular planes without a single break in continuity. Smaller switches, similarly constructed, have been successfully tested up to 2,000 c.p.s. at up to 20G acceleration.

25 Since the contact structure disclosed can move a predetermined amount without interrupting circuit continuity, it is clear that actuating forces can be drastically reduced since it is not necessary to hold the contact firmly in engagement. As a result, electromagnets, biasing springs, etc. can be reduced in size and weight thereby achieving an overall package which is 30 considerably smaller and while simultaneously achieving reliable operation when the switch is subjected to vibration.

In addition to its improved vibration resistance, the contact structure disclosed is ideally suited for a coaxial switch of the make-before-break type. Since the contact structure undergoes additional movement after it first makes electrical contact, a make-before-break structure can easily be attained without additional mechanical elements.

35 Turning now to FIGS. 4a, 4b and 4c, there is shown a coaxial switch of the make-before-break type. In the FIG. 4a, the coaxial switch is shown in deenergized position. Rocker arm 27 is pivoted all the way down on the right-hand side thereby forcing movable contact 20 into firm electrical and mechanical connection with inner conductors 18 and 18''. Flexible blade 23' is deflected up flush against rigid blade 22'. Movable contact 21, on the other hand, is completely disconnected from inner conductors 18' and 18'', so that the flexible blade 23 is in its natural, undeflected position.

40 In FIG. 4b, the coaxial switch is energized and rocker arm 27 begins to pivot downward at its left-hand end. After actuator 25 has traveled downward a short distance, flexible blade 23 first comes into connection with inner conductors 18' and 18''. At the same time, actuator 24 begins to rise thereby lifting movable contact 20 so that flexible blade 23' starts to assume its normal, undeflected position. At the point shown in FIG. 4b, however, flexible blade 23' is still deflected somewhat. At this point, the inner conductor 18' is electrically and mechanically connected to both of the outer conductors 18 and 18''. Thus, connection is established between inner conductors 18' and 18'', before contact is broken between inner conductors 18 and 18'.

45 Finally, in FIG. 4c, the switch is shown in its completely energized position. Rocker arm 27 has pivoted fully downward at its left-hand end and actuator 25 has moved the full extent of its downward travel to the point where the flexible blade 23 is completely deflected up to and substantially flush with rigid blade 22. Actuator 24 has risen to its full height thereby lifting movable contact 20 out of electrical connection with inner conductors 18 and 18' and the flexible blade 23' has returned to its normal, undeflected position. At this point, connection is firmly established between inner conductors 18' and 18'' whereas the circuit is now broken between inner conductors 18 and 18'.

50 In order to utilize the contact structure comprising the present invention in a coaxial switch of the break-before-make

type, it is only necessary to vary the internal dimensions to insure that the movable contacts travel sufficiently upward so as to disengage before the flexible blade of the other movable contact first comes into connection with its associated inner conductors.

FIG. 5 illustrates an alternative embodiment of the contact structure embodying certain concepts of the present invention. In the embodiment of FIG. 5, the rigid blade 22 and the flexible blade 23 are not connected together as was true in the preferred embodiment illustrated in the previous figures. Instead, the rigid blade 22 is, as before, firmly attached to actuator 25 but the flexible blade 23 is attached to one of the inner conductors 18' by riveting, spot welding, etc. In this embodiment, operation of the actuator 25 forces the rigid blade 22 downward until it comes into mechanical contact with the flexible blade 23 which then moves downward along with the rigid blade 22 until connection is established with inner conductor 18".

Since the flexible blade 23 is formed substantially as was shown in the preceding figures, it will be apparent that flexible blade 23 will engage inner conductor 18" before the rigid blade 22 has completed its downward travel so that, as in a previous embodiment, the rigid blade 22 can move a certain amount without interruption of circuit continuity.

FIG. 6 illustrates a still further alternative embodiment of the contact structure comprising the present invention. In the embodiment of FIG. 6, the actuator 32 may be formed of a semicircular rod of low-loss, nonconductive material. The rigid blade 22 is, as before, firmly attached to the actuator 32. However, a length of the actuator 32 extends below the rigid blade 22 and terminates in an enlarged portion 33.

The flexible blade 23 is also mounted on the actuator 32, but instead of being firmly secured to actuator 32, the flexible blade 23 is slidably engaged with actuator 32 so as to be free to travel reciprocally with respect to the actuator 32. A tension spring 34 extends from the enlargement 33 to the flexible blade 23 so as to pull flexible blade 23 away from rigid blade 22 in the position shown in FIG. 6.

As the actuator 32 begins to move downwardly, the rigid blade 22 and the flexible blade 23 will maintain the position shown in FIG. 6. However, when the flexible blade engages the inner conductors 18', 18", the flexible blade 23 will begin to move upwardly along actuator 32 until such time as it comes into contact with rigid blade 22. Additional travel of the actuator 32 results in the rigid blade 22 continuing downwardly until such time as it is substantially flush with the flexible blade 23. It is clear that the embodiment of FIG. 6 allows considerable movement of the rigid blade 22 since the tension spring 34 provides for additional travel of the rigid blade 22 with respect to the flexible blade 23 while circuit continuity is maintained.

In the embodiment of FIG. 6, the actuator 32 and the flexible blade 33 must be constructed so as to preclude rotation of the flexible blade 23. This can be accomplished, for example, by constructing the actuator 32 of a semicircular rod and then constructing the flexible blade 23 with a semicircular aperture 36 as shown in FIG. 7.

When flexible blade 23 is placed on the semicircular actuator 32, it is clear that rotation is precluded. It would also be possible to construct an actuator 32 with a key slot and then shape the aperture in the flexible blade 23 so as to contain a key which would then fit into a key slot and thereby prevent rotation. Alternatively, the actuator 32 could be constructed of any noncircular geometrical shape.

Although the present invention has been described with respect to several particular embodiments, the principles underlying this invention will suggest many additional modifications to those skilled in the art. Therefore, it is intended that the appended claims shall not be limited to the specific embodiment described, but rather shall cover all such modifications as fall within the true spirit and scope of the invention.

What I claim is:

1. A vibration-resistant contact structure comprising:
a. first and second fixed contacts;

5 b. a movable contact for selectively engaging at least one of said first and second fixed contacts, said movable contact including an elongated rigid blade of electrically conductive material and an elongated flexible blade of electrically conductive material;

10 c. means for mounting said flexible blade with the ends thereof biased out of engagement with the ends of said rigid blade; and,
15 d. actuating means for moving said rigid blade so as to resiliently urge at least one of the ends of said flexible blade into selective direct physical and electrical contact with said fixed contacts.

2. The vibration-resistant contact structure recited in claim 1 wherein said mounting means comprises means for securing said flexible blade to said rigid blade only at a point between the ends thereof.

3. The vibration-resistant contact structure recited in claim 1 wherein said mounting means comprises means for slidably mounting said flexible blade on an extension of said actuator between said rigid blade and said fixed contacts.

4. The vibration-resistant contact structure recited in claim 1 wherein said mounting means comprises means for securing one of the ends of said flexible blades to one of said fixed contacts.

5. The vibration-resistant contact structure recited in claim 1 wherein said rigid blade is substantially straight and said flexible blade is substantially arcuate.

6. A vibration-resistant contact structure comprising:
a. first and second fixed contacts; and
b. a movable contact for engaging said first and second fixed contacts, said movable contact including an elongated rigid blade of electrically conductive material and an elongated flexible blade of electrically conductive material, said flexible blade being secured to said rigid blade at a point between the ends of said rigid and flexible blades, said flexible blade being formed so that when joined the ends of said blades are normally separated by a predetermined distance, the ends of said flexible blade making direct contact with said fixed contacts on engagement and being deformed by such contact toward said rigid blade.

7. The contact structure recited in claim 6 wherein said rigid blade is substantially straight and said flexible blade is substantially arcuate.

8. A vibration-resistant coaxial switch comprising:
a. coaxial input and output connectors, each having an inner conductor and an outer conductor;
b. means for electrically interconnecting said outer conductors of said coaxial connectors;
c. a movable contact including an elongated rigid blade of electrically conductive material and an elongated flexible blade of electrically conductive material, said flexible blade being secured to said rigid blade at a point between the ends thereof, said flexible blade being formed so that when joined the ends of said blades are separated by a predetermined distance; and,
d. actuating means secured to said movable contact for reciprocally moving said movable contact so as to urge said flexible blade into direct physical and electrical connection with said inner conductors of said coaxial connectors.

9. A vibration-resistant coaxial switch comprising:
a. a housing including sidewalls and a bottom plate;
b. first and second input coaxial connectors mounted in said bottom plate, each having an inner conductor and an outer conductor;

65 c. an output coaxial connector mounted in said bottom plate and having an inner conductor and an outer conductor;
d. first and second movable contacts each including an elongated rigid blade of electrically conductive material and an elongated flexible blade of electrically conductive material, said flexible blade being secured to said rigid blade at a point between the ends of said rigid and flexible

- blades, said flexible blade being formed so that when joined the ends of said blades are separated by a predetermined distance;
- e. first and second actuating means secured to said first and second movable contacts; and,
- f. means for reciprocally moving said actuators to urge the flexible blade of said first movable contact into direct physical and electrical engagement with said inner conductors of said first input connector and said output connector and to urge the flexible blade of said second movable contact into direct physical and electrical engagement with said inner conductors of said second input connector and said output connector.

10. The vibration-resistant coaxial switch recited in claim 9 wherein said means for reciprocally moving said actuators comprises a rocker arm having said actuators pivotally mounted on said rocker arm.

5 11. The vibration-resistant coaxial switch recited in claim 9 wherein said first actuating means urges said first movable contact into engagement with said inner conductors of said first input connector and said output connector before said 10 second actuating means disengages said second movable contact from said inner conductors of said second input connector and said output connector.
